US0D1061800S

(12) **United States Design Patent** (10) **Patent No.:** **US D1,061,800 S**
(45) **Date of Patent:** **** Feb. 11, 2025**

(54) **BATTERY POWERED FLUID SPRAYER**

(71) Applicant: **Graco Minnesota Inc.**, Minneapolis, MN (US)

(72) Inventors: **Brian M. Mulgrew**, St. Francis, MN (US); **Jeffrey A. Earles**, Lakeville, MN (US)

(73) Assignee: **Graco Minnesota Inc.**, Minneapolis, MN (US)

(**) Term: **15 Years**

(21) Appl. No.: **29/805,921**

(22) Filed: **Aug. 31, 2021**

(51) LOC (15) Cl. **23-01**

(52) U.S. Cl.

USPC **D23/225**

CLAIM

The ornamental design for a battery powered fluid sprayer as shown and described.

DESCRIPTION

FIG. 1 is a first isometric view of a battery powered fluid sprayer;

FIG. 2 is a second isometric view of the battery powered fluid sprayer;

FIG. 3 is a third isometric view of the battery powered fluid sprayer;

FIG. 4 is a fourth isometric view of the battery powered fluid sprayer;

FIG. 5 is a left side view of the battery powered fluid sprayer;

FIG. 6 is a right side view of the battery powered fluid sprayer;

FIG. 7 is a rear elevational view of the battery powered fluid sprayer;

FIG. 8 is a front elevational view of the battery powered fluid sprayer;

FIG. 9 is a top plan view of the battery powered fluid sprayer; and,

FIG. 10 is a bottom plan view of the battery powered fluid sprayer.

The broken lines in the Figures represent portions of a battery powered fluid sprayer and form no part of the claimed design.

1 Claim, 10 Drawing Sheets
